ANTENNA MATCHING MODULE OR SIMILAR ARTICLE

Jerry C. Walderat, Buena Park, Calif., assignor to Communications Components Corporation, Long Beach, Calif.

Filed July 23, 1970, Ser. No. 24,097

Term of patent 14 years

Int. Cl. D14—03

U.S. Cl. D26—14

FIG. 2.

FIG. 3.

FIG. 4.

FIG. 5.

FIG. 6.

FIG. 1 is a top plan view of an antenna matching module or similar article showing my new design;

FIG. 2 is a side elevational view of the module looking from the direction indicated by arrow 2 in FIG. 1, showing one side of the module;

FIG. 3 is an end elevational view looking from the direction indicated by arrow 3 in FIG. 1, showing one end of the module;

FIG. 4 is a bottom plan view;

FIG. 5 is a side elevational view looking from the direction indicated by arrow 5 in FIG. 1, showing the other side of the module; and

FIG. 6 is an end elevational view looking from the direction indicated by the arrow 6 in FIG. 5, showing the other end of the module.

I claim:

The ornamental design for an antenna matching module or similar article, as shown.
